UNITED STATES PATENT OFFICE.

GEOORG ULLRICH, OF BROKEN HILL, NEW SOUTH WALES, AUSTRALIA.

MAGNETIC SEPARATOR.

1,037,563.

Specification of Letters Patent. Patented Sept. 3, 1912.

Application filed December 13, 1906. Serial No. 347,597.

To all whom it may concern:

Be it known that I, GEORG ULLRICH, a citizen of the Commonwealth of Australia, residing at Broken Hill, in the State of New 5 South Wales and said Commonwealth, have invented new and useful Improvements in Magnetic Separators, of which the following is a specification.

This invention relates to the magnetic separation of paramagnetic ore, or of substances of different degrees of positive magnetic susceptibility.

It has been devised for the purpose of providing a simple and highly efficient machine capable of producing ore concentrates of the highest grade.

One of the main features of this invention is that it provides, in a single mechanical construction a magnetic separator possessing 20 zones of different magnetic strength in a single magnetic field so that the ore particles, whether of the strongest or weakest magnetic susceptibility will be strongly attracted and held against the surface of certain separating rings, hereinafter described, while passing out of the magnetic field.

In order that the invention may be readily understood, it will be described by reference to the accompanying drawings in which:—

30 Figure 1 is a side elevation partly in section of a magnetic separator constructed according to this invention, while Fig. 2 is a plan thereof partly in section. Fig. 3 is a diagrammatic plan showing the construction 35 of a separating disk or ring used in the separator, and hereinafter particularly described. Fig. 4 is a section through said ring, also showing a pole piece of one of the electro-magnets and a conveyer belt forming part of the machine. Figs. 5 and 5^a are 40 diagrammatic views, illustrating the application of an armature in the magnetic field for the purpose of driving the moving parts of the separator, as hereinafter described.

45 The magnetic ore separator disclosed in Figs. 1 and 2 comprises a plurality of radial magnets 1, four being shown as a convenient number for purposes of illustration, any convenient number being used in practice and each being provided with a segmental pole piece 2, the whole being supported upon a standard 2^a. Above these magnets 1 are arranged one or more vertically adjustable separating rings 3 mounted 50 upon a shaft 4 and arranged to rotate in a

horizontal plane a short distance above the segmental pole pieces 2. The separating rings may be driven in any suitable manner as shown in Fig. 1 by means of an electric motor 8 having driving connection with a worm and gear 9. If preferred, an armature 9^a, see Figs. 5 and 5^a, such as is used in a dynamo-machine may be placed between the inner poles of the magnets 2^b of the separating magnets and be secured upon the 65 shaft 4 of the separating ring 3, thus eliminating any separate driving motor for transmitting motion to the said rings.

The material to be treated is fed into the magnetic field from a feed hopper or hoppers 5 or other suitable device, by means of a conveyer belt or belts 6 or other suitable feeding devices, in even regular quantities and in an evenly divided or comminuted state. As the ore passes through the magnetic field, formed by a pole piece 2 and the rotating separating ring or rings 3, the magnetic particles are attracted and held against the said rings 3 until they are carried over the edge of the belt 6 out of the influence of the magnetic field, when they fall into suitably disposed receptacles. The non-magnetic ore is discharged by the belt 6 into another receptacle.

70 The separating ring as shown in Fig. 1 may have its gathering face or surface wedged-shaped in cross section, or as shown in Figs. 3 and 4 the attracting surface of said ring may be flat and the ring itself provided with a circular series of small 75 annular rings concentrically arranged and projecting beyond the attracting or gathering surface of the ring 3. These small annular rings 3^c which are arranged concentrically are preferably formed of mild steel 80 or soft iron or other suitable material and in actual construction may consist of short pieces of pipe or tubing which are suitably secured to and carried by the separating ring 3. By using these short pieces of 85 tubing or pipes 3^c in conjunction with the separating ring 3, the lines of force passing through the pole pieces substantially upon parallel lines will be suddenly and strongly 90 condensed and concentrically converged 95 from the surface of the pole pieces 2 toward the edge of the tubes or pipes 3^c. This concentric concentration of the lines of force may be varied by making the ends of 100 the tubes or pipes 3^c square, pointed or 105 110

wedge-shape at their free ends. With this construction, great disturbances of the lines of force are produced in the field of magnetic force and separating action relative to the metalliferous particles is thereby considerably increased.

What is claimed is:—

1. In a magnetic separator, the combination with a magnet, of a member of magnetic material revolvably mounted over the pole piece of the magnet and magnetized by induction from the latter, a conveyer moving between the pole piece and member, said pole piece extending across the width of the conveyer.
2. In a magnetic separator, the combination of radially supported magnets having segmental pole pieces, of a rotating ring, of magnetic material over the pole pieces and magnetized by induction from the latter, conveyers each passing between the pole pieces and ring, the segmental pole pieces extending across the width of the conveyers.
3. In a magnetic separator, a series of electro-magnets having pole pieces in combination with a separating ring having a

plurality of circularly arranged series of concentric rings for condensing the lines of force within the magnetic field, and conveyer means for passing the material to be separated between the pole pieces and the separating ring.

4. In a magnetic separator, a separating continuous ring, a circularly arranged series of concentric rings of magnetic material projecting beyond the underface of the ring, which, in conjunction with the ring, cause the lines of force passing through the pole pieces, substantially upon parallel lines, to be suddenly and strongly condensed and concentrically converged from the surface of the pole pieces and means for feeding material between the ring and the pole pieces.

In testimony whereof I have hereunto set my hand in presence of two subscribing witnesses.

GEORG ULLRICH.
